DESIGN FOR A HEADDRESS

Maria Kincses, Cleveland, Ohio

Application March 15, 1945, Serial No. 118,501

Term of patent 14 years

(Cl. D3—13)

To all whom it may concern:

Be it known that I, Maria Kincses, a citizen of Hungary, residing at Cleveland, in the county of Cuyahoga and State of Ohio, have invented a new, original, and ornamental Design for a Headdress, of which the following is a specification, reference being had to the accompanying drawing, forming part thereof, wherein Fig. 1 is a front perspective view of a headdress showing my new design and Fig. 2 is a front perspective view of the headdress shown in Fig. 1 as when worn.

The back of the headdress is plain and unornamented.

I claim:

The ornamental design for a headdress, as shown and described.

MARIA KINCSES.
